CLAIM

The ornamental design for a toaster oven with egg cooker and coffee maker, as shown and described.

DESCRIPTION

FIG. 1 is a perspective view of a toaster oven with egg cooker and coffee maker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof in which a coffee pot is removed for convenience of illustration;

FIG. 9 is a perspective view thereof in which an egg cooking plate is removed for convenience of illustration; and,

FIG. 10 is a front elevational view in which an egg cooking plate is removed for convenience of illustration.
